LUG STRAP FOR LOOM PICKER STICKS

Herbert J. Barnett, Danielson, Conn.

Application October 17, 1934, Serial No. 748,689

5 Claims. (Cl. 139—153)

This invention relates to improvements in lug-straps for use with the picker-sticks of looms.

One object of the invention is to provide a metal lug-strap of relatively light weight which 5 is stronger and more durable in use than the usual straps made from rawhide, leather, fiber or laminated strips of fabric.

Another object of the invention is to provide 10 a lug-strap of the type indicated reinforced against strain and stress and embodying a buffer or shock-absorbing element to relieve the wear and deteriorating effect from the impact of the shuttle on the picker-stick.

Another object of the invention is to provide 15 a lug-strap of the type indicated having an improved construction of the shock-absorbing element or buffer-plug whereby to reduce the wear thereon while rendering it more efficient and durable in use over long periods.

Another object of the invention is to provide 20 a lug-strap of the type indicated which is more economical to manufacture than present types of straps now in use.

Further objects of the invention are set forth 25 in the following specification which describes a preferred form of construction of the invention, by way of example, as illustrated by the accompanying drawing. In the drawing:

Fig. 1 is a perspective view of my improved 30 lug-strap showing it partly broken away at the side to illustrate the buffer-plug located in its closed end;

Fig. 2 is a side view illustrating the lug-strap 35 connections for operating the picker-stick of the loom;

Fig. 3 is a plan view of the same;

Fig. 4 is a detailed edge view of the picker-stick showing the hold-up member applied thereto for retaining the strap in position relatively of the stick;

Fig. 5 is a composite perspective view of the parts of the buffer-plug or shock absorber shown in disassembled relationship; and

Fig. 6 is a perspective view illustrating a modification in the form of construction of the plug.

In accordance with present mill practice the lug-straps for picker-sticks of looms are constructed from rawhide, leather, fiber or laminated strips of duck or canvas fabric cemented together. It is well known to those versed in the weaving art that lug-straps are subjected to severe wear and in accordance with present methods of construction they have only a short life and require frequent replacement. The leather, fiber or fabric from which the straps are constructed becomes chafed and worn from contact with the picker-sticks and under the continuous hammering action of the shuttles the fabric or other material soon gives way and the strap must be discarded and replaced by a new

one. The present invention contemplates the construction of the strap from sheet-metal such as aluminum, steel or other like material of high tensile strength and treated to prevent corrosion under the damp conditions in mills.

Referring to the drawing, Fig. 1 illustrates the improved strap 2 as comprising a strip of sheet-metal bent into substantially U-shape to provide opposite parallel sides or arms 3—3, connected by an end piece 4. To reinforce and stiffen the structure, the side arms 3 are formed throughout a portion of their length with upper and lower flanges 5 folded outwardly from their edges. At the closed end of the strap the flanges 5 merge into extensions 6 of the rear wall or connecting strip 4, thereby increasing the dimension of this part of the strap to further augment the strength of the whole. The flanges 5, besides serving as a reinforcement for the sides of the strap, have a further important function, namely, to prevent wear on the hold-up member which supports the strap in operative relation to the picker-stick in the manner as later explained.

The forward end of the sides or arms 3 of the strap 2 are provided with slots or openings 7 for the reception of a stud or bolt 8 connecting the strap to a wooden bar or arm 9 from which the picker-stick is operated. As shown in Figs. 2 and 3 of the drawing, the wooden arm 9 is linked to a fabric or leather loop 10 by means of a bolt 11 and clamps 12. The loop 10 engages through a metal shackle or clevis 13 which is connected to a lever, not shown, for operating the picker-stick from the usual cam-motion in 35 the loom.

The bolt 8 which connects the strap 2 to the wooden arm 9 passes through clamping plates 14 abutting the sides of the arms 3 and having flanges at the top and bottom engaging across 40 the edges thereof to hold the plates in position. Preferably, the inner faces of the arms 3 of the strap 2 are provided with a plurality of protuberances 15 struck up from the metal by indenting the outer faces thereof as shown at 16. These 45 protuberances act as spurs to indent the wood of the arm 9 to effect a secure grip of the strap on the arm without chance of slippage should the bolt 8 become loosened.

As one feature of the present improvement 50 the buffer-plug 17 at the closed end of the strap 2 is constructed of rubber or an equivalent resilient material and protected by one or more sheaths of metal. As shown in Fig. 5 of the drawing, the plug 17 takes the form of a generally 55 cubical block having one of its sides convexed or rounded outwardly at 18. The material of the plug is skived or cut away on its sides at 19 to receive the triangularly-shaped lateral wings 22 of a metal sheath or protector 20. The 60

sheath 20 has a concavo-convex wall 21 adapted to fit closely against the convex face 18 of the block or plug 17 with its triangularly-shaped side wings 22 overlapping the sides thereof within 5 in the cut-out portions 19. A rivet 23 is passed through countersunk openings 24 in the wings 22 of the sheath 20 and through a laterally extending hole 26 in the plug 17, the ends of the rivet being thereafter headed over flush with the 10 sides of the sheath.

In some cases the resilient plug 17 is further sheathed with a metal plate 27 abutting its rearward face and having lateral flanges 28 folded across its sides. The flanges 28 are provided with 15 apertures 29 registering with holes 30, extending laterally through the plug 17. The plug 17 is positioned at the closed end of the strap 2 as illustrated in Figs. 1 and 2 and connected permanently therewith by means of rivets 31 passing through holes in the sides of the strap and the holes 29 in the sheath 27 and the plug 17. A secure joinder of the parts is thus effected and the surfaces of the rubber or other resilient material which are subject to contact are completely 20 sheathed with metal to prevent disintegration or distortion of the plug.

Fig. 6 illustrates a modified form of construction of the buffer-plug or block 17. In this alternative form a portion of the block may be 30 made of rubber vulcanized to greater hardness than the forward cushion portion of the block; or in other cases this rearward portion may be made of metal. In either case the forward, more resilient section 32 of the block is vulcanized or 35 cemented to the rearward section 33. The rearward portion 33 of the plug, when made of rubber, may be reinforced with strips of fabric embedded therein as indicated by broken lines in Fig. 6.

In applying the lug-strap to the loom it is 40 joined to the wooden arm 9 in the manner as described with its looped end enclosing the picker-stick 35. A hold-up member 36 of usual form is fastened to the rearward side of the stick 35 and, as illustrated most clearly in Fig. 4, its sides 45 are cut away to receive the flanged portions of the arms 3 of the strap 2. It will be noted by reference to this latter view of the drawing that the flanges 5 on the sides 3 of the strap 2 engage with the upper and lower edges of the cut-out portions of the hold-up member 36, thereby 50 providing extended bearing surfaces which reduce the wear both on the strap and the hold-up. Usually, the hold-up member 36 is constructed of rawhide, fiber or the like and secured 55 to the side of the picker-stick 35 by means of wood screws 37.

In use, the lug-strap is moved from the cam motion to actuate the picker-stick 35 with a 60 quick, sharp motion to throw the shuttle through the shed of the warp in the loom. This action is intermittent and continuous so that the lug-strap is subjected to considerable strain and extremely severe wear. The strap of the present invention, being made of metal, is highly resistant 65 to the strains and stresses imposed upon it, besides being proof against stretching or distortion. At the same time, its smooth sides are not liable to wear or cut into the picker-stick, especially since the edges of its arms are turned over in the flanges 5 which provide smooth, rounded corners. The shock and jar of the quick actuation of the picker-stick is taken by the re-

5 silent buffer-plug or block 17 with the metal sheath 20 protecting the yieldable material of the plug from wear under the contact of the picker-stick 35. Likewise, the rearward face of the plug or block 17 is protected by the metal shield or sheath 27 or, in other instances, by forming a section of the block of harder material as 10 illustrated in Fig. 6.

15 By the features above noted the present invention provides an extremely strong lug-strap which is practically proof against deterioration from wear under the constant pounding action of the picker-stick. No lining of wood, fiber or other resilient material is employed on the sides of the strap, yet the picker-stick is protected from wear and cutting under contact with the arms of the strap. The resilient buffer-plug 17 is also protected from the impact of the stick to render it more durable in use and to further prevent its 20 disintegration to reduce its cushioning effect. The flanges at the edges of the arms of the strap prevent cutting or marring the sides of the picker-stick, avoid wear on the hold-up and further reinforce the whole structure of the strap.

25 While my improved lug-strap is herein shown and described as embodied in a preferred form of construction, various modifications may be made in the shape and arrangement of its parts without departing from the spirit or scope of the invention. Therefore, without limiting myself in this 30 respect, I claim:

1. In combination, a metal lug-strap comprising opposite parallel arms joined together in a loop at one end, a rubber buffer-plug seated in the looped end of the strap, a metal sheath covering the forward contact face and two sides of the plug adjacent the contact face, and means for holding the sheath and plug in assembled relation in the loop of the strap. 35

2. In combination, a metal lug-strap comprising opposite arms connected at one end in a loop, a rubber plug seated in the closed end of the strap, said plug formed with a convex forward face, a sheath of concavo-convex form overlying the forward face of the plug with wings overlapping its sides, and a pin extending through the 40 wings of the sheath and the plug. 45

3. In combination, a metal lug-strap having opposite parallel arms joined together at one end in a loop, a resilient plug seated in the closed end of the loop, a metal sheath overlying the forward side of the plug, a second metal sheath overlying the rearward end of the plug, and means for securing the sheaths to the plug and the plug to the strap. 50

4. In combination, a metal lug-strap comprising opposite arms joined together at one end in a loop with flanges folded outwardly from the edges of the arms and merging into the rearward wall of the loop, a resilient plug seated in the closed end of the loop and having a convex end for engagement with the picker-stick, a metal sheath overlying the convex end of the plug, and means for securing the plug in place in the strap. 55

5. In combination, a metal lug-strap having opposite parallel arms joined together at one end in a closed loop, a buffer-plug seated in the closed end of the loop, said plug comprising a forward section of resilient material and a rearward section of harder material abutting the rearward wall of the strap, and a metallic sheath on the plug for engagement with the picker-stick. 60

70 HERBERT J. BARNETT.
